UNITED STATES PATENT OFFICE.

JOHN F. O'CONNOR, OF CHICAGO, ILLINOIS, ASSIGNOR TO W. H. MINER, INC., OF CHICAGO, ILLINOIS, A CORPORATION OF DELAWARE.

BUFFING MECHANISM.

Application filed April 22, 1927. Serial No. 185,883.

This invention relates to buffing mechanisms.

- An object of the invention is to provide a buffing mechanism including a main spring 5 resistance, and a friction system, and wherein a hollow integral housing is utilized which substantially encloses all of the operative parts of the mechanism, and wherein the friction system is bodily movable for setting up 10 a preliminary spring action to take care of relatively light shocks, and operates after predetermined movement to provide combined frictional and spring resistance to take up heavier shocks, the integral walls of the 15 housing being utilized as guides for the movable friction system which guides are so arranged as to maintain parts of the friction system in assembled relation with the housing.
- 20 A more particular object of the invention is to provide a buffing mechanism including an elongated hollow housing having a friction shell mounted for longitudinal movement therein, in conjunction with removable 25 members associated with the shell which serve as combined guides and stops for the shell, and in which liners are provided for the shell, having means by which they are secured to the shell, said means serving also 30 to lock the removable members in operative position.

Other and further objects of the invention will more clearly and fully appear from the description and claims hereinafter following.

- 35 In the drawings, forming part of this specification, Figure 1 is a longitudinal vertical sectional view of a fragment of an end platform of a railway car showing the invention in connection therewith. Figure 2 is a horizontal sectional view taken centrally through 40 the buffing mechanism. Figure 3 is a vertical sectional view of the invention corresponding substantially to line 3—3 of Figure 2. Figure 4 is an end elevational view of the buffing 45 mechanism. And Figure 5 is a transverse sectional view of the invention corresponding substantially to the line 5—5 of Figure 2.

As shown in the drawings, 10 represents the end platform of a railway car provided 50 with the usual pocket 11 in which the buffing mechanism indicated as a whole by the numeral 12, is disposed, said mechanism being supported by a web 13 extending across the bottom of the pocket. The usual center 55 stem is indicated at 14, and the buffer head at

15, the latter being carried on the usual side stems not shown.

The buffing mechanism 12 comprises, broadly speaking, a housing A; a main spring resistance B; a friction shell C; friction 60 shoes D; and a wedge E.

The housing A preferably comprises integrally formed top and bottom walls 16—16, side walls 17—17, and rear end wall 18, the front end of the housing being open. The 65 top and bottom walls are each provided with a centrally disposed rib 19, extending from a point slightly forwardly of the center of the housing, rearwardly, each rib being provided with a round bore 20 communicating at its 70 rear end with a socket 21 which opens outwardly through the rear wall 18 of the housing, said bore and socket being adapted for the reception of one of the retaining rods used in connection with the mechanism. The top 75 and bottom walls at their front ends are cut-out as indicated at 22—22, for co-operation with parts of the shell C. The side walls 17—17, on the inner surfaces of their forward ends, are each provided with a thickened portion in which is formed a groove 23, the groove terminating somewhat inwardly from the front end of each side wall in stop shoulders, indicated by the reference character 24. The side walls 17—17 are further provided with apertures 25—25, one of which 80 communicates with each of the grooves 23 in the side walls.

Disposed within the housing A is a main spring resistance B which comprises a pair 85 of heavy coiled springs arranged at opposite sides of the ribs 19, each of said springs having a smaller spring of the character indicated at 26 disposed on the interior thereof, all of the springs bearing upon the end wall 90 18, while the forward end portions of the springs bear upon a follower 27. The follower 27 is provided on its forward face with an annular rib 28, said rib being disposed about a boss 29, the parts 28 and 29 being provided for a purpose hereinafter described.

The shell C comprises top and bottom walls 95 30—30 of a width to fit the cut-out portions 22—22 in the top and bottom walls of the housing A, and with side walls 31—31, which are thickened to provide off-sets 32—32 which fit between the top and bottom walls of the housing, and the outer faces of which are disposed in relative close proximity to the inner surfaces of the side walls 17—17 of said 105 110

housing. The inner surfaces of the walls 31-31 of the shell C converge rearwardly, and upon each of said inner surfaces is disposed a liner 33. The side walls 31-31, and off-sets 32-32, of the shell C, are provided with transversely extending slots 34-34, each of said slots being of relatively narrow width, and appreciable height as best shown in Figures 2 and 5. Disposed in each of the slots 34 is a locking element or block 35, which in operative position projects outwardly beyond the outer surface of each of the off-sets 32-32 of the shell C, into one of the guide grooves 23, wherein the same is adapted to move longitudinally of the mechanism, forward movements of the same being limited by the shoulders 24 in the guides. Each of the liners 33 is provided with a lug 36 which enters one of the slots 34 in the side walls of the shell, the lugs 36, when the parts of the mechanism are in operative position, coming into contact with the adjacent end of one of the locking elements or blocks 35, whereby the latter is detachably held in position by the lug 36, the latter also having the function of maintaining the liner in position with reference to the shell C. The side walls of the shells are provided with longitudinally extending holes indicated at 37 for the purpose of lessening the weight of the shell.

The outer face of each of the liners 33 is provided with a friction surface indicated at 38, and cooperating with each of the liners 33 is one of the friction shoes D. The friction shoes are identically similar except for their opposite disposition, and each shoe includes a friction surface 39 disposed in contact with the friction surface 38 of the adjacent liner, and on the sides of each of the shoes D opposite the friction surface 39 is a wedge surface 40 adapted to co-operate with wedge surfaces formed upon the wedge E. The portions of the shoes D rearwardly of the wedge surfaces 40 are cut out to provide shoulders 41 upon which bears the forward end of an auxiliary coiled spring 42, the rear end of said spring bearing upon the front face of the follower 27, and being disposed about the boss 29 on said follower. The rear ends of the friction shoes D are disposed in line with the annular rib 28 and come into contact during one phase of operation of the mechanism.

The wedge D is provided with an abutting face 42 adapted to be engaged by the inner end of the center stem 14. The wedge D is maintained in position by means of the retainer bolts 43-43, the rear heads 44 of which are disposed in the sockets 21 formed in the ribs of the housing, each of the bolts 43 extending through the bore in the rib, through an aperture in the follower 27, and the ends of said bolts are provided with nuts 45 disposed in recesses 46-46 in the wedge, whereby the wedge is maintained in opera-

tive assembled relation with respect to the mechanism.

In operation, assuming inward movement of the center stem 14 under the influence of a relatively light shock transmitted thereto, the movement of the stem will be communicated to the wedge E. The wedge E through the shoes D bearing upon the liners 33-33, which are connected with the shell C, will move the shell C inwardly against the follower 27 which will compress the main spring resistance B the required extent, the retaining bolts 43 sliding rearwardly in the housing, and the movements of the shell being guided by the removable members 35-35 in the guide grooves 23-23. Under a light shock causing movement of the friction system a distance short of causing contact between the shell C and the stops provided by the rear walls of the cut out portions 22-22, no relative movement of the shoes and wedge with respect to the shell will occur, and all of the parts will resume their initial position when the actuating force is removed from the wedge, outward movement of the shell C being limited by reason of contact of the removable members 35-35 with the stops 24-24, while the wedge E will be limited in its forward movement by the heads 44-44 of the retaining bolts 43-43 coming into contact with the off-sets provided by the sockets 21-21. Under a relatively heavier shock, the wedge E, shoes D, and shell C, will travel inwardly as before described, until the shell C comes into contact with the rear walls of the cut-out portions 22-22, which will arrest rearward movement of the shell, and cause the wedge to move the friction shoes D inwardly against the follower 27, further compressing the main spring resistance D and setting up combined frictional and resilient resistance. The various parts are returned to their initial position under the influence of the main spring resistance B. The spring 42 has the function of maintaining the shoes and wedge in proper position and compensating for wear upon the friction surfaces.

While I have herein shown and described what I consider the preferred manner of carrying out the invention, the same is merely illustrative, and I contemplate all changes and modifications which come within the scope of the claims appended hereto.

I claim:

1. In a buffering mechanism of the character described, comprising an integral housing open at one end; a main spring means arranged in said housing; a shell mounted in said housing and movable longitudinally with respect thereto; removable members co-operating with the walls of said housing to provide guide means for said shell; a wedge; friction shoes co-operating with said wedge; liners for said shell having friction surfaces co-operating with said friction shoes; and

means for detachably connecting said liners to said shell, said means serving to maintain said removable members in operative position.

- 5 2. In a buffing mechanism of the character described, the combination with a housing provided with guide means having stop members associated therewith; a friction system disposed within said housing and movable 10 longitudinally with respect thereto; removable members associated with said friction system and co-operating with said guide and stop means, said removable members being maintained in position when the members of 15 said friction system are assembled; and means for maintaining the members of said friction system in assembled condition.

3. In a buffing mechanism of the character described, comprising a housing having top, 20 bottom, side and end walls, said housing being open at one end, the top walls of said housing being cut out from the front ends thereof rearwardly, and the side walls of said housing being provided with guides; a shell longitudinally movable of said housing and limited 25 in its rearward movement by said cut-out portions; means associated with said shell co-operating with said guide, to guide said shell and limit the forward movement thereof; a wedge and friction elements co-operating 30 with said shell; means anchored to the housing for limiting forward movement of said wedge and friction elements; and yieldable means arranged in said housing and co-operating 35 with said shell and said wedge and friction elements.

4. In a device of the character described, the combination with a housing having top, 40 bottom, side and end walls, the top walls of said housing being cut out for a limited distance rearwardly from the front ends thereof and said side walls being provided with com-

bined guide and stop means; a shell disposed within said housing and longitudinally movable with respect thereto, the side walls of 45 said shell being provided with transversely extending slots; liners secured to the side walls of the shell; removable members arranged in said slots engaged by said liners and retained thereby and co-operating with 50 said combined guide and stop means; a wedge and friction elements co-operating with said shell and adapted to maintain said liners and said removable members in operative relation when in assembled condition; means for holding said wedge and friction elements assembled; and yieldable means co-operating 55 with said shell and said wedge and friction elements.

5. In a device of the character described, 60 the combination with a housing; of a shell disposed within said housing and longitudinally movable with respect thereto; means for limiting movement of said shell inwardly of said housing; means for limiting movement of said shell outwardly of said housing, 65 said means including members removably carried by said shell and engaging stop means on said housing; liners for said shell, having projections for anchoring the same to the 70 shell, said projections engaging said members; a wedge and friction elements co-operating with said shell and engaging said liners to hold the same assembled with the shell and maintain said removable members in position 75 for cooperation with said stop means when in assembled condition; and means for maintaining said wedge and friction elements in assembled relation with respect to said shell. 80

In witness that I claim the foregoing I have hereunto subscribed my name this 18th day of April, 1927.

JOHN F. O'CONNOR.
